VALVE DEVICE

Ferris T. Harrington, Detroit, Mich., assignor to
 Vickers Incorporated, Detroit, Mich., a corpora-
 tion of Michigan

Application February 29, 1940, Serial No. 321,426

4 Claims. (Cl. 121—46.5)

This invention relates to power transmissions, particularly to those of the type comprising two or more fluid pressure energy translating devices, one of which may function as a pump and another as a fluid motor.

This invention is more particularly concerned with a combined four-way directional valve and foot valve for use with a fluid motor for operating a machine tool slide or other driven device. Certain types of motors and load devices have been heretofore provided with a foot valve, so called, arranged in the return line from the motor and so constructed as to maintain a predetermined back pressure on the fluid exhausting from the motor. Where the foot valve is between the four-way valve and the motor a check valve is necessary to permit free return flow to the motor in the opposite direction. Where the foot valve is between the four-way valve and the tank the back pressure is imposed during both directions of movement although it is only necessary in one direction.

An object of the present invention is to provide a combined directional control valve and foot valve in a unitary body.

A further object is to provide in a valve of this character improved circuit arrangements permitting free flow around the foot valve without check valves under all operating conditions when the foot valve is not required.

Further objects and advantages of the present invention will be apparent from the following description, reference being had to the accompanying drawing wherein a preferred form of the present invention is clearly shown.

In the drawing:

Figure 1 is a longitudinal cross section of a valve embodying a preferred form of the present invention.

Figure 2 is a diagrammatic view of a power transmission system embodying a preferred form of the present invention.

Figure 3 is a detailed cross sectional view on the line 3—3 of Figure 1.

Referring now to Figure 2, there is shown a pump 10 adapted to be driven by a suitable prime mover, such as an electric motor 12. The pump 10 withdraws fluid from a tank 14 through a suction conduit 16 and delivers it to a delivery conduit 18. The latter has a relief valve 20 of conventional construction for bypassing oil to the tank through a conduit 22 whenever a predetermined pressure is exceeded in the delivery conduit 18.

The conduit 18 extends to the pressure port 55

24 of a combined four-way and foot valve generally designated 26. The latter has a tank connection 28 which communicates with the tank 14 through a conduit 30. The valve 24 is provided with two motor connections 32 and 34 (shown in dotted lines in Figure 1) and which are connected by conduits 36 and 38 to the opposite ends of a fluid motor 40. The latter comprises a cylinder in which a piston 42 is slidable, the rod 44 of which carries a suitable head or other work device generally designated as 46.

The valve 24 is provided with a pair of projecting stems 48 and 50 adapted to be operated by solenoids 52 and 54 through the medium of levers 56 and 58. For the purpose of controlling the energization of solenoids 52 and 54 an electric circuit is provided as follows: A momentary contact starting switch 60 when closed connects between a line L¹ running from one side of a suitable source and a conductor 62. The latter extends to the coil of a holding relay 64 adapted when energized to close a circuit extending from line L¹ through a conductor 66 to the solenoid 54 the other side of which is connected to the other side of the line L². The holding circuit for the relay 64 extends from the coil thereof by a conductor 68 through the holding contacts of the relay and by a conductor 70 to the normally closed contacts of a double-throw limit switch 72. The latter is adapted to be actuated by a cam 74 on the head 46 when the latter reaches the lower limit of its stroke.

The normally open contacts of the limit switch 72 connect between line L¹ and a conductor 75 which leads to the operating coil of a second holding relay 76. The relay 76 when energized closes a circuit between line L¹ and a conductor 78 extending to solenoid 52, the other side of which is connected to line L². The holding circuit of relay 76 extends from the coil thereof by a conductor 80 through the holding contacts and by a conductor 82 to a normally-closed limit switch 84 and line L¹. The latter is adapted to be opened by the cam 74 when the head 46 is in its fully raised position, as illustrated. Each of the solenoids 52 and 54 is preferably provided with internal return springs, not shown, whereby the spool of valve 26 is maintained in a central position when neither solenoid is energized.

Referring now to Figure 1, the valve 26 comprises a body 86 having a bore 90 within which is slidably mounted the spool 92 which carries the stems 48 and 50. The latter are provided with slots 96 within which the lower ends of the levers

56 and 58 extend. Suitable abutment screws 98 are provided for adjusting the position to which the solenoid will shift the spool 92. Spring-pressed plungers 100 are mounted in bores 102 in the spool 92 and serve to maintain the levers 56 and 58 in close contact with the abutment screws.

The bore 90 is provided with a plurality of annular ports arranged along its length as shown in Figure 1. Thus the annular port 104 constitutes the pressure port of the valve and is connected by a passage, not shown, in the body with the pressure connection 24 of Figure 2. On either side of the pressure port 104 are motor ports 106 and 108 which communicate with the motor connections 32 and 34. At the outside of the motor ports there are provided tank ports 110 and 112, as shown.

The spool 92 is provided with three lands 122, 124 and 126 which in the neutral position of the valve lie opposite the ports 112, 104 and 110 respectively. The spool 92 is also provided with a central bore 128 which connects between radial cross bores 130 and 132. The latter in the neutral position of the valve open into the ports 104 and 110 respectively.

In the lower part of the body 88 there is formed a second valve bore 114 within which the spool 116 of the foot valve is mounted. The bore 114 is provided with two annular grooves 118 and 120 which form inlet and outlet ports respectively for the foot valve. The spool 116 is provided with a land 134 which normally closes the port 120 from communication with the port 118 shown in the left hand position of the spool 116. When the spool is shifted to the right by means later to be described, communication is opened from port 118 to port 120.

Mounted on the body 88 at the left hand end of bore 114 is an end cap 136 within which is formed a small cylinder 138. The latter carries a small floating piston 140 adapted to abut against a projection 142 formed on the left hand end of the spool 116. The left hand end of cylinder 138 communicates by a passage 144 with the port 118 so that whatever pressure exists in the latter will be exerted on the left hand face of the piston 140.

At the right hand end of bore 114 an end cap 146 is mounted. The latter carries an adjusting screw 148 for the purpose of adjustably determining the force of a spring 150 which is mounted within the hollow portion of the screw 148 and abuts against the right hand end of the spool 116. Suitable locking and acorn nuts 152 and 154 are provided on the projecting end of the screw 148. A replaceable stop washer 156 is mounted between the body 88 and the face of the end cap 146 to serve both as an abutment for the spool 116 and for the screw 148 to limit the maximum travel of both elements. A seepage drain passage 158 is formed in the end cap 146 and communicates with the port 120.

The body 88 is provided with a cored passage 160 communicating between the tank port 110 and the tank connection 28 and passing across the annular port 120 at the bore 114. Also the body is formed with a second passage 162 connecting between the tank port 112 and the inlet port 118 at the bore 114.

In operation, assuming the pump 10 to be driven by the motor 12, oil is withdrawn from the tank 14 through suction conduit 16 and delivered through the conduit 18 to port 24 of the valve 26. With the spool 92 in the neutral position illustrated the full pump delivery is by-

passed to tank through the radial bore 130, the central bore 128, bore 132, passage 160, and connection 28 to the tank conduit 30. The pump is thus maintained unloaded during all times that the spool 92 is in neutral position.

When it is desired to advance the head 46 downwardly the starting switch 60 is closed thus energizing the relay 64. The latter picks up closing its holding circuit through the normally closed contacts of switch 72. The relay 64 also energizes the solenoid 54 thus rocking the lever 58 clockwise to shift the spool 92 to the left. The pump delivery is accordingly directed from pressure port 104 to motor port 106 where it is delivered through the connection 32 and conduit 36, to the head end of the motor 40. Oil pushed out of the lower end of motor 40 returns through the conduit 38, connection 34, port 108, tank port 112 and passage 162 to the inlet chamber 118 of the foot valve.

In order for the oil to pass out of chamber 118 the valve spool 116 must shift to the right. This is accomplished by the pressure building up in chamber 118 and being transmitted through passage 144 to the small cylinder 138 where it pushes the piston 140 and spool 116 to the right against the force of spring 150. The degree of pressure required to thus open the foot valve depends upon the adjustment of spring 150, and this adjustment is normally sufficiently high so as to prevent the gravity load of the head 46 from pulling the piston 42 downwardly.

As the piston 42 and head 46 complete their downward stroke the cam 74 rides onto the limit switch 72 thus opening the holding circuit for relay 64 and at the same time energizing the relay 76. The latter picks up, closing its own holding circuit through limit switch 84 which is now closed. The relay 76 also energizes the solenoid 52 through the circuit 78 thus shifting the lever 56 counterclockwise which carries the spool 92 to its right hand position. Oil from the pump delivery line is now directed from port 104 to port 108 where it leaves through connection 34 and conduit 38 to enter the lower end of motor 40. The piston 42 and head 46 accordingly retract upwardly discharging oil through the conduit 36, connection 32, ports 106 and 110, and passage 160 to the tank conduit 30. It will be noted that during the return stroke the discharging oil from the motor is free to pass to the tank without the back pressure being imposed by the foot valve. This is accomplished without the use of a check valve.

When the piston 42 reaches the upper limit of its stroke the cam 74 again contacts the limit switch 86 opening the latter to deenergize the solenoid 76. The spool 92 accordingly returns to center position under the influence of the spring-centering means associated with the solenoids 52 and 54, and the pump is again unloaded as described at the start of this operation.

It will be noted that during the unloaded condition of the pump the pump delivery passes freely to tank through the passage 160 and is unrestricted by the foot valve.

While the form of embodiment of the invention as herein disclosed constitutes a preferred form, it is to be understood that other forms might be adopted, all coming within the scope of the claims which follow.

What is claimed is as follows:

1. A combined four-way and foot valve for controlling the flow of fluid to and from a hydraulic motor comprising a body having a plu-

rality of valve bores, a four-way valve spool slidably mounted in one bore, a pressure-responsive foot valve mounted in the other bore, means forming a pressure port, a pair of motor ports and a pair of tank ports at the first bore, said spool being shiftable to selectively connect the pressure port with either motor port and simultaneously connect the other motor port with one or the other of the tank ports, means forming a tank connection to said body, an unobstructed passage between said connection and one of the tank ports, said passage communicating with the outlet of the foot valve, and a passage connecting the other tank port with the inlet of the foot valve.

2. A combined four-way and foot valve for controlling the flow of fluid to and from a hydraulic motor comprising a body having a plurality of valve bores, a four-way valve spool slidably mounted in one bore, a pressure responsive foot valve mounted in the other bore, means forming a pressure port, a pair of motor ports and a pair of tank ports at the first bore, said spool being shiftable to selectively connect the pressure port with either motor port and simultaneously connect the other motor port with one or the other of the tank ports, said four-way valve further having a neutral position in which the pressure port is cut off from both motor ports, means forming a tank connection to said body, an unobstructed passage between said connection and one of the tank ports, said passage communicating with the outlet of the foot valve, and a passage connecting the other tank port with the inlet of the foot valve, said four-way valve having an unloading passage effective in neutral

position to connect the pressure port with that tank port which communicates freely with the tank connection.

3. A directional control valve for a fluid motor comprising a body and shiftable valve member forming a reversing valve with a pressure port, motor ports and a plurality of tank ports arranged for selective connection of the pressure port with either motor port and the simultaneous connection of another motor port with one or another of the tank ports, means forming an open tank passage from one tank port, means forming a second passage from another tank port, and a pressure-responsive foot valve in the second passage and arranged to block the second passage at pressures below a predetermined value and to connect the second passage to tank at higher pressures.

4. A directional control valve for a fluid motor comprising a body and shiftable valve member forming a reversing valve with a pressure port, motor ports and a plurality of tank ports arranged for selective connection of the pressure port with either motor port and the simultaneous connection of another motor port with one or another of the tank ports, means forming an open tank passage from one tank port, means forming a second passage from another tank port, a pressure-responsive foot valve in the second passage and arranged to block the second passage at pressures below a predetermined value and to connect the second passage to tank at higher pressures, and means for bypassing the pressure port to said one tank port when the directional control valve is in neutral position.

FERRIS T. HARRINGTON.
